C. E. ERICKSON,
THERMOMETER PROTECTOR AND SHIPPING GUARD.
APPLICATION FILED JAN. 2, 1920.

1,397,412.

Patented Nov. 15, 1921.

UNITED STATES PATENT OFFICE.

CLAUS EDWARD ERICKSON, OF DES MOINES, IOWA.

THERMOMETER PROTECTOR AND SHIPPING-GUARD.

1,397,412.

Specification of Letters Patent. Patented Nov. 15, 1921.

Application filed January 2, 1920. Serial No. 349,116.

To all whom it may concern:

Be it known that I, CLAUS E. ERICKSON, a citizen of the United States, and a resident of Des Moines, in the county of Polk and State of Iowa, have invented a certain new and useful Thermometer Protector and Shipping-Guard, of which the following is a specification.

My invention relates to a thermometer protector and shipping guard, so constructed and arranged that the guard may be quickly placed over the breakable portion of the thermometer and be securely fastened thereto, yet the guard being readily and easily removed at the will of the operator. It is known that when thermometers are packed for shipping, it necessitates the placing of the thermometer in a carton or packing it in excelsior or some other material, so that the thermometer will not become broken in shipping and handling.

My device is of simple, durable and inexpensive construction, and can be quickly and easily attached or detached from the thermometer.

The object of my device is to provide a thermometer so adapted that a metal guard may be placed over the breakable part and be detachably fastened to the thermometer, so that the breakable part will not be broken in handling or shipping.

A further object is to provide a shipping guard, so constructed that parts of the thermometer are utilized for holding the guard over the breakable part of the thermometer.

Still a further object is to provide a support for a thermometer, which has a recess in it for receiving the thermometer and a card having the series of graduations on it, the thermometer being fastened to the card and the card being riveted to the support by means of eyelets, so that the eyelets may be used for fastening the guard in such position that it will substantially cover the recess and thus prevent the thermometer from accidentally being broken in handling or shipping.

Still a further object is to provide a support for a thermometer which has a recess formed in it, the edges of the recess being beveled, the thermometer and card having the graduations on it being placed in the recess and then riveted to the support, a guard adapted to substantially cover the recess for protecting the breakable parts of the thermometer, the guard being provided

with sides, the lower edges of which are beveled, so that when the beveled edges of the guard rest against the beveled edges of the recess, it will be an easy matter to lightly force the guard into such position that the edges will rest in the recess and thus require only two places of fastenings to securely hold it to the support.

With these and other objects in view, my invention consists in the construction, arrangement and combination of the various parts of the device, whereby the objects contemplated are attained, as hereinafter more fully set forth, pointed out in my claims and illustrated in the accompanying drawings, in which:

Figure 1 shows a plan elevation of my thermometer.

Fig. 2 shows an end view of the same.

Fig. 3 shows a side elevation of my thermometer with the shipping guard being shown in section to better illustrate the construction.

Fig. 4 is a sectional view taken on the line 4-4 of Fig. 3, showing the beveled edges of the shipping guard and the coacting beveled edges of the support.

Fig. 5 shows a plan view of the blank from which the shipping guard is formed.

Fig. 6 shows a plan view of the guard after it is formed.

Fig. 7 shows an end view of the guard, showing the tapered fingers, with which the guard is fastened to the thermometer support.

In the accompanying drawings, I have used the reference numeral 10 to indicate generally a thermometer support preferably made of sheet metal. The support or back 10 is provided with openings 11 and 12, so that the thermometer may be hung in position. The support 10 is provided with a recess 13. The edges of the recess are beveled at 14. The beveled portion 14 extends slightly up above the remainder of the support 10. A thermometer 16 is placed in the recess 13 adjacent to a series of graduations 15. In the present form of my device, I have shown the thermometer 16 fastened to a card 14^a and have provided clamps 17 for holding the thermometer to the card. The card is secured to the support by means of the rivets 18. The rivets 18 have preferably a central opening and are commonly known as eyelets. The blank 19 from which the guard is bent is provided with fingers 20 and sides

21. The sides 21 are curved slightly upwardly at 22 to form a beveled surface. The fingers 20 are adapted to be received in the rivets 18. When the fingers 20 are placed 5 in the rivets 18 and the extended portion of the fingers 20, which extends below the bottom of the recess, is bent over, it will securely hold the guard over the thermometer, and thus prevent anything from striking the 10 thermometer and breaking it.

The sides 21 of the guard or blank 19 are resilient, so that they may be yieldingly forced into the recess, and the outward tension of the sides 21 will cause the curved 15 portion 22 to snugly fit against the beveled edges of the recess. In this way any variation in size of the recess will be readily taken care of. The sides 21 of the guard being of resilient material will practically make the 20 guard fit various sizes of recesses.

The sides 21 slightly taper upwardly, as is shown by the dotted lines 23 in Fig. 5. The tapered sides are provided because it is necessary to have a greater distance between the 25 guard and the support near the lower end than is necessary near its upper end on account of the bulb 24 of the thermometer extending slightly out past the upper surface of the beveled edges 14.

30 It will be seen that after the guard is placed in position, substantially as is shown in Fig. 4 of the drawings, and the fingers 20 are forced through the rivets 18 and then bent over, it will prevent the guard from being accidentally displaced, and also prevent anything from striking against the thermometer and breaking it. By having the beveled edges 14 in the recess 13 and the co-acting beveled edges 22 on the guard fit 35 snugly against each other, it prevents any movement of the guard relative to the support, and thus requires only two fastenings 40 to hold the guard in proper position.

The fingers 20 may be made of comparatively light material, as they do not hold the guard in position when it comes to side strain, but only tend to hold the guard directly above the thermometer. The sides 21 fitting slightly into the recess take care 50 of all the ordinary side strain and the like.

Some changes may be made in the construction and arrangement of the various parts of my improved device without departing from the essential features and purposes of my invention, and it is my intention 55 to cover by my claims any modified forms of structure or use of mechanical equivalents, which may be reasonably included within their scope.

60 I claim as my invention:

1. In a device of the class described, a means for protecting a thermometer tube mounted on a support formed with a recess, said recess being designed to receive said 65 thermometer tube, said first means comprising

ing a guard adapted to be placed over said thermometer tube, and means for detachably fastening said guard to said support, said last means comprising fingers formed on said guard adapted to extend through said support. 70

2. In a device of the class described, a means for protecting a thermometer tube on a support formed with a recess, said means comprising a guard adapted to be placed 75 over the thermometer tube and to be spaced slightly therefrom, said guard having resilient side members, the lower edges of said side members being curved, so that they may be yieldingly forced into said recess, and 80 means for detachably fastening said guard to said support.

3. In a device of the class described, a means for protecting a thermometer tube on a support formed with a recess, the bottom 85 of said recess having openings therein, said means comprising a guard adapted to be placed over the thermometer tube, said guard having extending fingers formed on the ends thereof and at right angles thereto, 90 said fingers being designed to be received in said openings and to extend therethrough, so that when said extended portion is bent over, it will securely hold said guard in proper relation to said support. 95

4. In a device of the class described, a means for protecting a thermometer tube on a support formed with a recess, the bottom of said recess having openings therein, said means comprising a guard adapted to substantially cover said recess and having means thereon for extending through said openings for holding said guard in position relative to the support for protecting the thermometer tube from being broken in shipping. 100

5. In a device of the class described, a means for protecting a thermometer tube on a support formed with a recess, said recess having beveled edges and having its bottom 110 provided with openings, said means comprising a guard adapted to substantially cover said recess, said guard having upwardly tapered sides, said sides having their lower edges beveled so that they may easily 115 fit against the beveled edges of said recess, fingers extending from said guard and at right angles thereto, said fingers being adapted to extend through said openings, and to be bent over for anchoring said guard to said support. 120

6. In a device of the class described, a means for protecting a thermometer tube on a support formed with a recess, said recess having beveled edges and having its bottom 125 provided with openings, said means comprising a guard adapted to substantially cover said recess, said guard having upwardly tapered resilient sides, said sides having their lower edges beveled so that they may 130

easily fit against the beveled edges of said recess, fingers extending from said guard and at right angles thereto, said fingers being adapted to extend through said openings, so that when they are drawn tightly, it will force the resilient sides outwardly thus making it possible for the guard to completely cover recesses of various sizes.

7. In a device of the class described, a means for protecting a thermometer tube mounted on a support, said first means comprising a guard adapted to be placed over

said thermometer, the guard being provided with a top and side members, and means for detachably fastening said guard to said support, whereby said guard will protect the thermometer tube against breakage, said last means comprising a pair of fingers adapted to extend through said support and have their ends bent, whereby they may be anchored to said support.

Des Moines, Iowa, October 24, 1919.

CLAUS EDWARD ERICKSON.
